DESIGN FOR AN OVERSHOE

Bates B. Craver, Waterbury, Conn., assignor to United States Rubber Company, New York, N. Y., a corporation of New Jersey

Application January 14, 1939, Serial No. 82,360

Term of patent 3½ years

To all whom it may concern:

Be it known that I, Bates B. Craver, a citizen of the United States of America, residing at Waterbury, County of New Haven, and State of Connecticut, have invented a new, original, and ornamental Design for an Overshoe, of which the following is a specification, reference being had to the accompanying drawing, forming part thereof, wherein:

Figure 1 is a perspective of one side of the overshoe; and

Figure 2 is a front view of the top portion of the overshoe.

I claim:

The ornamental design for an overshoe, as shown.
